UNITED STATES PATENT OFFICE.

MARGUERITE KAESELAU, OF PROVINCETOWN, MASSACHUSETTS.

DESIGN FOR A RAG DOLL.

60,097.

Specification for Design.

Patented Dec. 27, 1921.

Application filed May 12, 1921. Serial No. 469,050. Term of patent 3½ years.

To all whom it may concern:

Be it known that I, MARGUERITE KAESELAU, a subject of the Kingdom of Sweden, residing at Provincetown, in the county of Barnstable and State of Massachusetts, have invented a new, original, and ornamental Design for a Rag Doll, of which the following is a specification, reference being had to the accompanying drawing, forming part thereof.

Figure 1 is a front view of a rag doll, showing my new design.

Fig. 2 is a side view of a rag doll showing my new design.

Fig. 3 is a back view of a rag doll showing my new design.

I claim:

The ornamental design for a rag doll as shown.

MARGUERITE KAESELAU.
